US0D1055295S

(12) **United States Design Patent** (10) **Patent No.:** **US D1,055,295 S**
(45) **Date of Patent:** **** Dec. 24, 2024**

(54) **WRIST BRACE**

(71) Applicant: **SHENZHEN RUI TRADE E-COMMERCE CO., LTD.**, Shenzhen (CN)

(72) Inventor: **Eric Woo**, Shenzhen (CN)

(73) Assignee: **SHENZHEN RUI TRADE E-COMMERCE CO., LTD.**, Shenzhen (CN)

(**) Term: **15 Years**

(21) Appl. No.: **29/938,210**

(22) Filed: **Apr. 19, 2024**

(51) **LOC (14) Cl.** **24-02**

(52) **U.S. Cl.**

USPC **D24/190**

(57) **CLAIM**

The ornamental design for a wrist brace as shown and described.

DESCRIPTION

FIG. 1 is a perspective view of a wrist brace showing my new design;

FIG. 2 is another perspective view thereof;

FIG. 3 is a front elevational view thereof;

FIG. 4 is a rear elevational view thereof;

FIG. 5 is a left side elevational view thereof; and,

FIG. 6 is a right side elevational view thereof.

The broken lines in the drawings depict portions of the wrist brace that form no part of the claimed design.
